UNITED STATES PATENT OFFICE.

JESSE MINOR COX, OF GREENSBORO, PENNSYLVANIA.

POCKET MATCH-SCRATCHER.

1,088,325.

Specification of Letters Patent. Patented Feb. 24, 1914.

Application filed June 16, 1913. Serial No. 773,976.

To all whom it may concern:

Be it known that I, JESSE MINOR Cox, a citizen of the United States, residing at Greensboro, in the county of Greene and State of Pennsylvania, have invented certain new and useful Improvements in Pocket Match-Scratchers, of which the following is a specification, reference being had to the accompanying drawings.

10 This invention relates to an improved pocket match scratcher and has for its primary object to provide improved means secured to the pocket flap wherewith the match head is adapted to frictionally engage to cause the same to ignite.

Another and more specific object of the invention resides in the provision of a sheet of emery or other friction material sewed or adhesively secured to the under side of 20 a pocket flap with which the heads of the matches are adapted to be engaged as they are drawn from the pocket, and a protective flap or lining to prevent the side of the coat pocket from being worn by the engagement 25 of the emery sheet therewith.

A further object of the invention is to produce a simple and effective device of the above character which may be readily applied to a pocket flap at very small cost.

30 With the above and other objects in view, this invention consists in the novel features of construction and the combination and arrangement of parts to be hereinafter more fully described, pointed out in the appended claim, and shown in the accompanying drawing, in which—

Figure 1 is a side elevation of a portion of a coat or other garment having a pocket, showing the flap raised; and Fig. 2 is a 40 vertical section, the flap being down in its normal position.

Referring in detail to the drawing, 5 designates the coat or other garment provided with a pocket 6.

45 7 designates the usual flap which overhangs and closes the upper end of the pocket. To the under side of the flap 7 a sheet of emery or other friction material, indicated at 8, is secured at its edges by stitching the same thereto, though it will be obvious that glue or other suitable adhesive may be employed for this purpose. A lining 9 of any suitable material is also stitched to the pocket flap along one edge of the emery 50 sheet adjacent the attached edge of the

pocket flap and, when the flap is in its normal position it is disposed between the emery sheet and the outer side of the pocket. This lining acts as a protection for the fabric and prevents the side of the pocket from 60 being worn by the frictional engagement of the emery sheet therewith.

From the above description it is thought that the manner of use of my invention will be obvious.

When it is desired to ignite the match head for lighting a cigar, cigarette or any other purpose, the pocket flap is raised and the hand inserted therein to withdraw at 70 match. As the hand is withdrawn the match head is brought into contact with the emery sheet so that the friction thus produced will cause the same to flame. Thus the necessity of striking the match upon the trouser's leg or other places and marring the same 75 is avoided.

When the pocket flap hangs downwardly in its normal position, the match scratcher is invisible so that the same does not detract in any manner from the neat appearance 80 of the garment.

It will be obvious that as the invention is of an extremely simple nature, the same can be provided at extremely small cost.

It is to be understood that my invention includes the manufacture of these improved match scratchers independent of or detachable from a garment and that any means may be employed to detachably or otherwise secure the device in its applied position.

What I claim is:

The herein described match scratcher comprising in combination with a garment pocket provided with a flap; a friction sheet 95 of less length than the flap secured to the under side thereof, and a protecting lining fabric of greater length than the friction sheet secured to said flap along one edge of the friction sheet and normally disposed between said sheet and the wall of the pocket to protect the pocket wall against wear by the engagement of the friction sheet therewith.

In testimony whereof I hereunto affix my 105 signature in the presence of two witnesses.

JESSE MINOR COX.

Witnesses:

FRANK B. KRAMER,
Mrs. JOHN C. KRAMER.
